JOHN L. McMILLAN, OF SYRACUSE, NEW YORK, ASSIGNOR TO McMILLAN BOOK COMPANY, OF SYRACUSE, NEW YORK, A CORPORATION OF NEW YORK

LOOSE-LEAF BINDER

Application filed October 13, 1928. Serial No. 312,273.

This invention relates to a new and improved loose leaf binder in which the sheets are retained in position on prongs or arcuate posts.

In using loose leaf binders it is frequently desirable that the leaves in the binder be disposed in such a way that they themselves will constitute a visible index. When a binder is being used for this purpose the length of the sheets in the binder is usually considerably less than the height of the binder so that the leaves may be positioned in the binder in overlapping relation, leaving a portion of each sheet exposed to view so that any indicia thereon may be visible when the binder is open.

When a binder is being used as a visible index record for certain classes or types of accounts it is frequently necessary to insert or remove one or more of the sheets from the binder, when, for example, it is desired to add a record sheet or when the particular account represented by a sheet or sheets has been closed or when it is desired to transfer record sheets to another binder. When this occurs it is often desirable to place new sheets in the binder either in proper alphabetical order or at the bottom of the binder or elsewhere, and in order to do this it is necessary that one or more of the sheets in the binder shall be moved either upwardly or downwardly to provide a space for the new sheets.

In order to accomplish such transfer of sheets it is very desirable that some means be provided whereby one or more sheets may be moved vertically from one set of prongs to another set of prongs in one operation and without actual removal of the sheets from the prongs.

As a new and improved way in which sheets may be transferred vertically from one set of prongs to another set of prongs I have discovered that such a result may be most quickly and most easily accomplished if the binder is provided with opposed sets of prongs, one carried on one part of the back member of the binder and the other carried on the other part of the back member of the binder, such parts of the back member being hinged together so that the opposed sets

of prongs may be moved towards and from each other as desired. I have further discovered that with this arrangement of prongs the vertical transfer of sheets in the binder may be best accomplished if a means is provided whereby one of the sets of prongs may be moved angularly in a transverse direction with respect to the opposing set of prongs.

For use with such a binder I provide sheets which carry on one longitudinal edge a series of apertures so spaced as to permit the entrance therethrough of the prongs of the binder, and I preferably provide the sheets with additional apertures positioned between the apertures through which the prongs extend.

When the binder is in the closed position it will be obvious that a sheet may be moved from one side of the binder to the other side of the binder, the prongs of the binder at all times remaining in the same apertures in the sheet in which they were initially placed. If the two parts of the back member of the binder are opened or rocked apart on their hinged connection to such an extent that the opposed sets of prongs will have merely their end portions in overlapping relation so that one set of prongs will have been withdrawn from the apertures in the sheet, and a sheet is moved from the set of prongs on which it is positioned to the opposing set of prongs, the prongs which were withdrawn from the apertures in the sheet will again enter the same apertures in which they were positioned when the binder was in the closed position.

If, however, when the opposed sets of prongs have merely their end portions in overlapping relation as just described, one of the sets of prongs is moved angularly in a transverse direction in relation to the other set of prongs so as to shift the end portions longitudinally of the hinge a distance equal to the space between two apertures in a record sheet and a sheet is moved onto the prongs which are in such angular relation from the opposing set of prongs which remain in the normal position, such sheet will be moved diagonally of the binder so that when the prongs which were removed from the apertures in the sheet again enter apertures in the sheet they will

100

- not enter the apertures in which they were formerly positioned but will enter apertures adjacent thereto, with the result that the sheet will have moved vertically in the binder.
- 5 When the prongs which were moved angularly are returned to the normal position and the binder closed, the sheet which was thus transferred will have changed its vertical position in the binder.
- 10 The main object of my invention is to provide a means whereby opposed sets of prongs in a binder may be so moved in relation to each other that when a sheet is transferred from one set of prongs to another set of prongs its vertical position in the binder will be changed by such transfer.
- 15 Another object of my invention is to provide a means which will permit such transfer of a sheet but which will accomplish this result in such a way that the sheet being transferred will at all times have prongs extending through apertures in such sheet.
- 20 In using binders of this type where the relative position of one set of prongs is changed in relation to the other set of prongs temporarily while the leaves are being transferred from one set of prongs to another it frequently happens that the person using the binder will attempt to close the same before
- 25 the movable set of prongs has been returned to its normal position with the result that the ends of the prongs will strike the leaves in the binder with resulting damage to the leaves, and another object of my invention
- 30 is to provide a means whereby the movable prongs will be automatically returned to their normal position when the binder is closed so that it will be impossible for the person using the binder to close the same with the prongs
- 35 out of the normal position.
- 35 Further I have found that it is desirable to provide a means for locking or holding the back members in three distinct relative positions about the connecting hinge, namely,
- 40 when the binder is closed, when it is in the intermediate position with the ends of the prongs overlapping to permit transfer of leaves from one set of prongs to the other set of prongs, and when it is in the open position to permit leaves to be inserted on or withdrawn from the prongs. Therefore, to facilitate manipulation of the binder I have
- 45 provided a means whereby when the binder is initially unlocked and the opposed sets of
- 50 prongs moved away from each other they will be automatically locked in the second or intermediate position without attention from the operator, such means permitting further opening of the binder only after the operator
- 55 has again tripped the latch to permit the further opening of the binder to the third or open position in which position it will be automatically locked. To facilitate the closing of the binder my locking means is so designed that the binder may be closed from

either the open or intermediate position without the necessity of its being unlocked by the operator and when so closed will automatically be locked in the closed position.

Binders of the character described are frequently of considerable size and weight and usually have their backs covered by leather, canvas or other material. In use such binders are usually placed on a table or desk and when it is desired to move such a binder on a table or desk or when it is desired to unlock the binder and move the sets of prongs in relation to each other the friction between the back of the binder and the table or desk is such that it makes the manipulation or moving of the binder difficult and another object of my invention is to provide a means which will permit the binder to be moved on a table or desk and to be opened and closed with the minimum of friction between it and the table or desk thus rendering more easy the use of the binder.

Other objects and advantages relate to the size, shape and arrangement of parts all as will more fully appear from the following description taken in connection with the accompanying drawings in which:

Figure 1 is a perspective view partially broken away of my binder in a closed position.

Figure 2 is a top plan view of my binder with the covers partially broken away and with the prongs in the closed position.

Figure 3 is a top plan view partially broken away and partially in section of my binder with the prongs in the intermediate position.

Figure 4 is a section on line 4—4 of Figure 7.

Figure 5 is an enlarged view partially broken away of one end of the sectional view shown in Figure 7.

Figure 6 is a section on line 6—6 of Figure 7.

Figure 7 is a section on line 7—7 of Figure 9.

Figure 8 is a section on line 8—8 of Figure 3.

Figure 9 is a section on line 9—9 of Figure 2.

Figure 10 is a section on line 10—10 of Figure 2.

Figure 11 is a section on line 11—11 of Figure 5.

Figure 12 is a top plan view, partially broken away, of my binder in the intermediate position showing three leaves in position on prongs.

Figure 13 is a top plan view, partially broken away, of my binder in the intermediate position and with one set of prongs in the pivoted position and the other set of prongs in the normal position, one loose leaf being in position on the pivoted prongs and two leaves in position on the opposed prongs.

Referring to Figure 1, my binder 1 com-

prises opposed rear housings 2 and 3 hingedly connected together as by a piano hinge 4. A cover 5 is hingedly connected to housing 2 as by a piano hinge 6 and a cover 7 is similarly hingedly connected to housing 3 as by a piano hinge 8 as shown in Figure 2. Housing 2 has rollers 9 and 10 journaled in spaced relation in its outside longitudinal edge, rollers 9 and 10 extending outwardly from housing 2 so that when the binder 1 is in position on a table or desk it will be supported on rollers 9 and 10 and housing 2 will be held in spaced relation from such desk or table. Housing 3 is similarly constructed with rollers 11 and 12 journaled therein to hold housing 3 in spaced relation to a supporting desk or table. As shown, housings 2 and 3 are preferably rectangular in cross-section, housing 2 carrying end plates 13 and 14 and housing 3 carrying end plates 15 and 16. End plate 16 is provided with a superposed frame member 17 for the reception of a card carrying any desired indicia.

Housing 3 is provided with a plurality, in this case shown as eleven, of arcuate prongs 18 in spaced relation which extend upwardly from the outer longitudinal edge of top plate 19. The lower portions of prongs 18 extend inwardly toward the inner longitudinal edge of housing 3 and have their inner ends bent vertically to enter apertures in a locking plate 20 fixed in housing 3 to hold prongs 18 from any relative movement with respect to themselves or to housing 3.

As perhaps may best be seen from Figures 7 and 8 a rod 21 is positioned adjacent the inner longitudinal edge of housing 3 and has rotatably mounted thereon a pair of arcuate notched latches 22 and 23, latches 22 and 23 extending through slots 24 and 25 into housing 2 for a purpose hereinafter to be described. Rod 21 also carries at approximately the midpoint thereof a cam plate 26 arcuate in shape and which extends into housing 2 through a slot 27 for a purpose herein-after to be described. Top plate 19 of housing 3 is provided on its outer longitudinal edge, see Figure 3, with a plurality, in this case shown as ten, of apertures 28 in spaced relation and positioned between prongs 18.

Housing 2 is provided with a plurality, in this case shown as ten, of arcuate prongs 29 which extend downwardly through top plate 30 of housing 2 and are rotatably mounted in sleeves 31—31 affixed to the inner face of the outside longitudinal side of housing 3, see Figures 7, 8 and 9. The lower ends of prongs 29 extend inwardly towards the inner side of housing 2 and have their inner ends bent upwardly and extending through apertures in a slidable plate 32 so that the movement of plate 32 longitudinally of housing 2 will cause the inner ends of prongs 29 to also be moved longitudinally of housing 2 with the result that prongs 29 will be piv-

oted in sleeves 31 to cause simultaneous longitudinal movement of the upper ends of prongs 29 in relation to the housing 2. To accomplish the longitudinal movement of plate 32 I provide a bellcrank 33 pivotally mounted on plate 32 by means of a pivot pin 34 which extends upwardly through a slot 35 in top plate 30 of housing 2. One end of bellcrank 33 is provided with a knob 36 and the other end of bellcrank 33 is formed with a U-slot 70 in registration with a headed pin 37 fixed in top plate 30 so that when bellcrank 33 is moved about its pivot 34 the end of bellcrank 33 carrying the U-slot will be held against longitudinal movement with respect to housing 2 with the result that plate 32 will be moved longitudinally of housing 2 in a direction depending upon the direction of rotation of bellcrank 33.

Prongs 29 are positioned, in their normal position, in staggered relation to prongs 18 so that when the binder is in the closed position prongs 29 will be positioned between adjacent prongs 18 with their outer ends in registration with apertures 28 in top plate 19. Similarly prongs 18 will be positioned between adjacent prongs 29 with their outer ends in registration with apertures 38 which are provided in top plate 30 for their reception.

As perhaps may best be seen from Figures 3 and 4 plate 32 is provided on its central portion with a pair of spaced vertically extending lugs 39 which when the binder is in the closed position receive between them the main body of cam plate 26 which prevents any longitudinal movement of plate 32. When, however, the binder is in the intermediate position as shown in Figure 3 the comparatively narrow end 40 of cam plate 26 will be positioned between the lugs 39 which will permit limited longitudinal movement of plate 32 until one of the lugs 39 contacts with the narrow portion 40 of cam plate 26. When plate 32 is in position with a lug 39 contacting with the narrow portion 40 of cam plate 26 the prongs 29 will be in the pivoted or transferring position. When the parts are in this relative position and the binder is closed by moving the housings 2 and 3 towards each other on hinge 4 the cam plate 26 will be moved forwardly between lugs 39 with the result that the lug 39 which is in contact with the narrow portion 40 of cam plate 26 will move from the narrow portion 40 towards and on to the main body of cam plate 26 carrying with it plate 32 which in turn will cause the pivotal movement of prongs 29 to their normal position.

To assist in expediting the movement of prongs 29 from the pivoted to the normal position I provide, see Figures 3 and 7, an arm 41 which has one end pivotally mounted in housing 2 by means of a stationary pin 42 and which has its other end spring-pressed, by means of 125

spiral spring 44 which is interposed between arm 41 and the outer side of housing 2, toward the vertical portion of a prong 29 which extends upwardly to plate 32. The end of arm 41 which is in registration with the prong 29 is provided with a U-slot 43 in which prong 29 is received when prong 29 is in the normal position. When the plate 32 has been moved longitudinally of housing 2 to cause the pivoting of prongs 29 the portion of the prong 29 which is in the U-slot 43 of arm 41 will be moved out from such U-slot 43 into registration with a portion of arm 41 adjacent prong 29, such movement being permitted because of the fact that the arm 41 will be moved about the pin 42 against the action of the spring 44. In Figure 3, I show in full lines arm 41 and prong 29 in the normal position and in dotted lines prong 29 and arm 41 when the plate 32 has been moved longitudinally of housing 2. When the plate 32 starts to move from the pivoted to the normal position of prongs 29 the prong 29 which is in registration with the end of arm 41 will enter the U-slot 43 and the action of the spring 44 which tends to force arm 41 against prong 29 will accelerate the movement of prong 29 to the bottom of slot 43 and in consequence will accelerate the longitudinal movement of plate 32.

For the purpose of locking the housings 2 and 3 in selected positions in relation to each other I provide latches 22 and 23 with a plurality, in this case shown as three, of notches 45 and 46 respectively which notches 45 and 46 are adapted to be engaged by a slidable plate 47 adapted to be moved into and out of engagement with notches 45 and 46 by its longitudinal movement in housing 2. For the purpose of holding plate 47 normally in engagement with notches 45 and 46 I provide a spring 48 having one end attached to plate 47 and the other end affixed to housing 2.

For the purpose of moving plate 47 longitudinally in housing 2 for the purpose of releasing latches 22 and 23 so that housings 2 and 3 may be moved in relation to each other I provide an unlatching means which, as perhaps may best be seen from the enlarged view shown in Figure 5, consists of a bellcrank 49 pivotally mounted in housing 2 by means of a pivot pin 50. A slot 51 is provided in bellcrank 49 in which slot is positioned a fixed pin 52 for the purpose of limiting the movement of bellcrank 49 about its pivot 50 by contact of the pin 52 with the ends of slot 51.

A second bellcrank 53 is pivotally mounted on bellcrank 49 normally having one end overlying slot 51 and the other end extending laterally from bellcrank 49 into a slot 54 in plate 47. Bellcrank 53 is yieldingly held in this position by means of a spiral spring 55 interposed between the inner end of bellcrank 53 and the upper end of bellcrank 49, bellcrank 49 having its upper end

of a hook shape as —a— to function as an anchor for one end of spring 55. I also provide a spiral spring 55' having one end fixed by a pin 56 to housing 2 and having its other end engaged with a hook-like projection —b— provided on bellcrank 49 for the purpose of yieldingly holding bellcrank 49 in a position permitting the entrance of one end of bellcrank 53 into slot 54 of plate 47. I also provide on bellcrank 49 an upwardly extending tab 57 to permit the manual rotation of bellcrank 49 about its pivot 50, tab 57 extending upwardly through a slot in cover 30 of housing 2.

When the binder is in the closed position and it is desired to open the same the relation of the parts just described is such that when bellcrank 49 is moved about its pivot 50 one arm of bellcrank 53 will engage an end of slot 54 of plate 47 and the further pivoting of bellcrank 49 will cause bellcrank 53 to move plate 47 longitudinally of housing 2 to withdraw plate 47 from the first notches 45 and 46 in latches 22 and 23 which will permit latches 22 and 23 to move outwardly through slots 24 and 25. The position of bellcrank 53 on bellcrank 49 is such that a portion of one arm of bellcrank 53 overlies slot 51 so that a further pivoting of bellcrank 49 will cause one arm of bellcrank 53 to contact with pin 52 and cause bellcrank 53 to pivot on bellcrank 49 thereby withdrawing the end of bellcrank 53 which was positioned in slot 54 from such slot to permit the return movement of plate 47, such return movement being caused by the action of spring 48. The position of parts will then be as shown in dotted lines on Figure 5. A further opening of the binder will bring into registration with plate 47 the second notches 45 and 46 in latches 22 and 23 so that the binder will be then automatically locked in the second or intermediate position. If it is desired to open the binder still further it will be necessary to again rotate bellcrank 49 in the manner just described to move plate 47 in relation to housing 2 to release it from the notches 45 and 46 with which it is engaged.

When the binder is in the open position and it is desired to close the same it is not necessary to manipulate bellcrank 49 because of the fact that the intermediate and outer notches 45 and 46 have one of their sides inclined in each case with the result that the movement of housings 2 and 3 towards each other will cause plate 47 to ride outwardly along the curved sides of notches 45 and 46 to release latches 22 and 23 and permit the binder to be closed.

As a "booster" or aid to the operator in separating housings 2 and 3 I provide in one end of housing 3, as perhaps may best be seen from Figure 9, a bellcrank 58 pivotally mounted to one end of housing 3 by pivot pin

59 and having one end extending outwardly through a slot in cover 19 of housing 2 and having pivotally mounted on its other end a pusher bar 60 adapted, when bellcrank 58 is moved about the pivot 59, to move outwardly through a slot 61 in housing 3 and contact with the side of housing 2 to force housings 2 and 3 apart. When housings 2 and 3 are returned to the closed position housing 2 will contact with pusher bar 60 to force it inside of housing 3 thus causing bellcrank 58 to be moved about its pivot 59 and returned to its normal position.

The relation of parts is such that when slide 47 is positioned in the first notch 45 of latch 22 and the corresponding notch 46 of latch 23 the housings 2 and 3 will be in the closed position as shown in Figures 2 and 9 with the ends of prongs 18 in apertures 38 and with the ends of prongs 29 in apertures 28. When the binder is in the transferring position slide 47 will be in the intermediate notches 45 and 46 of latches 22 and 23 respectively to hold housings 2 and 3 in the relative position shown in Figures 3 and 8 in which position the ends of prongs 18 slightly overlap the ends of the opposing prongs 29.

When the binder is in this position bellcrank 33 may be pivoted to cause the pivotal movement of prongs 29 and the relation of parts is such that when the pivotal movement of prongs 29 has been effected the ends of the prongs 29 will have been moved longitudinally of housing 2 to a position midway between the normal position of the ends of prongs 29 and the position of the ends of adjacent prongs 18. In Figure 3 I have shown prongs 18 and 19 in the normal position in full lines and I have shown the position of prongs 29, after their rotation has been effected, in dotted lines. It will be understood that altho I have shown in Figure 3 by dotted lines the position of prongs 29 after they have been pivoted in one direction that such prongs may, if desired, be pivoted in the opposite direction the same distance from their normal position. That is to say, the ends of prongs 29 may as desired be moved towards either one of the two prongs 18 between which they are positioned.

For the purpose of explaining the operation of my device and the way in which the vertical movement of a leaf in the binder is accomplished I have shown in Figure 12 my binder in the intermediate position with the prongs 29 in their normal position substantially parallel with prongs 18, and I have shown in position on prongs 18 three loose leaves 62, 63 and 64, and in Figure 13 I have shown my binder in such intermediate position with the prongs 29 shifted angularly in one direction and with leaf 62 after it has been transferred from prongs 18-18 to prongs 29-29, leaves 63 and 64 remaining in position on prongs 18-18.

Referring to Figure 12, if leaf 62 be moved from prongs 18-18 to prongs 29-29 and the binder is then closed, the leaves 62, 63 and 64 will not have changed their vertical position in relation to the binder because of the fact that when the book is closed prongs 29-29 will enter the same apertures in the leaves 62, 63 and 64 in which they were positioned before the binder was opened. That is to say, prong 29' will enter aperture —c— in leaf 62. Prongs 29-29 being operatively connected together, an explanation of the cooperating movements of an individual prong 29' with the leaf 62 will explain the operation of my device, it being understood that each of prongs 29 cooperate with apertures in leaf 62 in the same manner as does the prong 29'.
70
75

When it is desired to change the vertical position of a sheet in the binder, the sheet or sheets, the position of which is to be changed, are placed on prongs 18-18 as shown in Figure 12. The prongs 29-29 are then shifted angularly about their stationary pivots to the position shown in Figure 13 and the sheet to be transferred, as sheet 62, is moved from prongs 18 onto prongs 29-29. Prongs 29-29 being in the shifted position during such movement of leaf 62, prong 29' will not, as just described, enter aperture —c— in leaf 62 but will enter the next adjacent aperture —d—, the prongs 29 entering apertures next adjacent to the apertures in which they were formerly positioned. When the prongs 29-29 have been moved back to the normal position or when the binder is closed the leaf 62 will have been moved vertically in the binder because of the fact that prongs 18-18 and 29-29 will then be positioned in apertures in leaf 62 adjacent to the apertures in which they were formerly positioned.
80
85
90
95
100
105

In Figure 13 I have shown in heavy lines prongs 29-29 shifted in one direction and I have shown in dotted lines such prongs shifted angularly in the opposite direction. If leaf 62 were moved from prongs 18-18 to prongs 29-29, when the latter were in the position indicated by such dotted lines, prong 29' would enter aperture —e— in leaf 62 with the result that the vertical movement of leaf 62 would be in a direction opposite to the direction in which it had been moved when prong 29' was in a position to enter aperture —d—. That is to say, the direction of the vertical movement of leaf 62 may be changed as desired.
110
115
120

Although the prongs are rocked or angularly shifted about a stationary axis, the preferred movement being the distance between the centers of two adjacent openings in a record sheet, the angle of movement is so small that the ends of the prongs are shifted substantially longitudinally of the hinge for the back members or vertically of the book.
125
130

and their inclination is not sufficient to obstruct in any way the transfer of sheets from the stationary prongs to the shiftable prongs, when the latter are angularly shifted in either direction from normal position, or vice versa.

It will be understood that the materials of which my device are constructed may be varied as desired as may be the exact position and relation of the various parts thereof 10: without departing from the spirit of my invention, for although I have shown and described a specific structure and form of part as an exemplification of an embodiment of my invention I do not desire to restrict myself to the exact size, shape or arrangement 15: of parts as various changes may be made within the scope of the appended claims.

I claim:

1. In a device of the class described, opposed housings hingedly connected together, 20: a plurality of prongs positioned in one housing, a plurality of prongs mounted on vertical pivotal axes in the other housing and joined together for simultaneous movement, 25: said prongs being normally in parallel relation to the first-named prongs, means for simultaneously pivoting the last-named prongs about said axes, and means actuated by movement of the housings in relation to 30: each other for moving the pivoted prongs to their normal positions.

2. In a device of the class described, opposed housings hingedly connected together, 35: a plurality of prongs positioned in one housing, a plurality of prongs mounted on vertical pivotal axes in the other housing and joined together for simultaneous movement, 40: said prongs being normally in parallel relation to the first-named prongs, means for simultaneously pivoting the last-named prongs about said axes, means actuated by movement of the housings in relation to each other for moving the pivoted prongs to their 45: normal positions including a slide and a cam-carrying member adapted to engage.

3. In a device of the class described, opposed housings hingedly connected together, 50: a plurality of prongs positioned in one housing, a plurality of prongs mounted on vertical pivotal axes in the other housing and joined together for simultaneous movement, 55: said prongs being normally in parallel relation to the first-named prongs, means for simultaneously pivoting the last-named prongs about said axes, means actuated by movement of the housings in relation to each other for moving the pivoted prongs to their normal 60: positions including a slide having spaced lugs positioned thereon, and a cam-carrying member coacting with the lugs.

4. In a device of the class described, opposed housings hingedly connected together, 65: a plurality of prongs positioned in one housing, and joined together for simultaneous movement, said prongs being normally in

parallel relation to the first-named prongs, a plurality of prongs mounted on vertical pivotal axes in the other housing, means for simultaneously pivoting the last-named prongs about said axes, means actuated by 70: movement of the housings in relation to each other for moving the pivoted prongs to their normal positions including a slide having spaced lugs positioned thereon, a cam-carrying member adapted to engage the lugs, 75: and a spring-pressed pivoted arm coacting with the slide.

5. A loose leaf book comprising a pair of back members, a longitudinal hinge connecting said back members, series of prongs carried by each back member and normally extending parallel with each other, the prongs of each series extending in closed position of the book from one back member to the other back member, said series of prongs being relatively shiftable to and from overlapping position by movement of said back members about said hinge, means for shifting the prongs of one series angularly about vertical axes, and means operative upon 85: movement of the back members to close the book for automatically shifting the movable prongs to normal position.

6. A loose leaf book comprising a pair of back members, a longitudinal hinge connecting said back members, series of prongs carried by each back member and normally extending parallel with each other, the prongs of each series extending in closed position of the book from one back member to the other back member, said series of prongs being relatively shiftable to and from overlapping position by movement of said back members about said hinge, means for shifting the prongs of one series angularly about 95: a vertical axis and means operative upon movement of the back members to close the book for automatically shifting the movable prongs to normal position.

7. A loose leaf book comprising a pair of back members, a longitudinal hinge connecting said back members, series of prongs carried by each back member and normally extending parallel with each other, the prongs of each series extending in closed position 100: of the book from one back member to the other back member and spaced apart a distance conforming to a plurality of spaced openings in a loose leaf adapted to be mounted on said prongs, said series of prongs shiftable to and from overlapping position by movement of said back members about said hinge, means for shifting the prongs of one series angularly about vertical axes to bring 105: the ends of the movable series of prongs into alignment with a different series of openings in loose leaves from those openings with which said prongs were normally aligned to permit shifting of a sheet or sheets to a different position in the book, and means oper- 110: 115: 120: 125: 130:

ative upon movement of the back members to close the book for automatically shifting the movable prongs to normal position.

8. A loose leaf book comprising a pair of back members, a longitudinal hinge connecting said back members, series of prongs carried by each back member and normally extending parallel with each other, the prongs of each series extending in closed position 5 of the book from one back member to the other back member and spaced apart a distance conforming to a plurality of spaced openings in a loose leaf adapted to be mounted on said prongs, said series of prongs shift- 10 able to and from overlapping position by movement of said back members, about said hinge, means for shifting the prongs of one series angularly about a vertical axis to bring the ends of the movable series of prongs into 15 alignment with a different series of openings in loose leaves from those openings with which said prongs were normally aligned to permit shifting of a sheet or sheets to a different position in the book, and means opera- 20 tive upon movement of the back members to close the book for automatically shifting the movable prongs to normal position.

9. In a device of the class described, opposed back members hingedly connected to- 25 gether, a plurality of arcuate prongs positioned on each back member, a bell-crank pivotally mounted on one back member and a pusher bar having one end pivotally mounted on an arm of the bell-crank and having its 30 other end adapted to contact with the other back member whereby the pivotal movement of the bell-crank will cause the back members to move about their hinge.

10. In a device of the class described, op- 35 posed housings hingedly connected together and each being provided at their opposite ends with an end plate, a cover hingedly connected to each housing, and a frame positioned on an end plate of a housing and 40 adapted to receive an indicia-carrying card.

11. In a device of the class described, op- 45 posed back members hingedly connected together, a plurality of arcuate prongs positioned on each back member and normally in 50 parallel relation, means for moving the prongs on one back member obliquely in relation to the prongs on the other back member, and means actuated by movement of the back members in relation to each other 55 for moving the movable prongs to their normal position.

12. In a device of the class described, op- 60 posed back members hingedly connected together, a plurality of arcuate prongs positioned on each back member and normally in 65 parallel relation, means for simultaneously moving the prongs on one back member obliquely in relation to the prongs on the other back member, and means actuated by movement of the back members in relation

to each other for moving the movable prongs to their normal position.

13. In a device of the class described, op- 70 posed back members hingedly connected together, a plurality of arcuate prongs positioned on each back member and normally in parallel relation, means for moving the prongs on one back member obliquely in relation to the prongs on the other back member, and means actuated by movement of the back 75 members in relation to each other for moving the last-mentioned prongs to their normal position including a slide connected to the movable prongs and a cam-carrying member adapted to engage the slide. 80

14. In a device of the class described, op- 85 posed back members hingedly connected together, a plurality of arcuate prongs positioned on each back member and normally in parallel relation, means for simultaneously moving the prongs on one back member obliquely in relation to the prongs on the other back member, and means actuated by movement of the back members in relation to each other for moving the last-mentioned prongs to their normal position including a slide connected to the movable prongs and a cam-carrying member adapted to engage the slide. 90

15. In a device of the class described, op- 95 posed back members hingedly connected together, a plurality of prongs positioned on one back member, a plurality of prongs on the other back member, means for moving the last-mentioned prongs obliquely in relation to the prongs on the other back member, and means actuated by movement of the back members in relation to each other for moving the movable prongs to their normal position including a slide having spaced lugs positioned thereon connected to the movable prongs, and a cam-carrying member adapted to engage the lugs. 100

16. In a loose leaf binder adapted to con- 105 tain record leaves having a plurality of spaced apertures in one edge, two series of impaling prongs adapted to normally enter given apertures in loose leaves, means for mounting and guiding the series of impaling prongs for movement towards and from each other, means for moving one series of impaling prongs into a position adapted to register with apertures in loose leaves different from those with which they are normally 110 adapted to register to effect longitudinal shifting of the leaves with reference to each other, and means actuated by the movement of the series of impaling prongs towards each other for moving the movable prongs to the normal position. 115

17. In a loose leaf binder adapted to con- 120 tain record leaves, two series of impaling prongs normally in parallel fixed spaced relation, means for mounting and guiding the series of impaling prongs for movement to- 125 130

wards and from each other, means for moving one series of impaling prongs to bring their ends into a different spaced relation with regard to the prongs of the other series, 5 and means actuated by the movement of the series of impaling prongs towards each other for moving the movable prongs to the normal position.

18. A loose leaf binder adapted to contain 10 record leaves comprising a pair of back members, a set of prongs mounted on each back member and extending substantially to the other back member in closed position of the book, hinge means connecting the back members to effect movement of said sets of prongs to and from overlapping position, means permitting shifting of one of said sets of prongs in another direction to permit longitudinal shifting of leaves which the book is adapted 20 to contain, and means actuated by moving said back members about said hinge in closing the book to return said set of prongs from said shifted position to original position.

19. A loose leaf binder comprising opposed 25 back members joined together for relative movement, a latch secured to one back member, means on the other back member releasably engaging the latch, means engaging the last-named means and adapted to move it out 30 of engagement with the latch, and means for automatically disengaging the second-named means from the first-named means when the first-named means has been disengaged from the latch to permit its return to the engaging 35 position.

20. A loose leaf binder comprising opposed back members joined together for relative movement, a latch secured to one back member, a bar slidably mounted on the other 40 back member and adapted to engage the latch, means engaging the bar for moving the bar out of engagement with the latch, and means for disengaging such means from the bar when the first-named means has been disengaged 45 from the latch to permit its return to the engaging position.

21. A loose leaf binder comprising opposed back members joined together for relative movement, a latch secured to one back 50 member, a bar slidably mounted on the other back member and adapted to engage the latch, a shoulder on the bar means on the last-named back member for moving the bar out of engagement with the latch including a bell-crank pivotally mounted on such back member, a second bell-crank pivotally mounted on the first-named bell-crank and having one end adapted to engage the shoulder on the 55 bar, means for pivoting the first-named bell-crank with the other bell-crank engaging the bar, and means for pivoting the second-named bell-crank whereby it will move out of engagement with the bar when the bar has been 60 moved out of engagement with the latch to 65

permit the bar to return to the engaging position.

22. In a loose leaf binder, a pair of frame pieces, hinge means for interconnecting said frame pieces, and latching mechanism carried by one of said frame pieces and cooperating with the other of said frame pieces, comprising a pair of arcuate arms spaced longitudinally of said frame pieces and pivoted to one of said frame pieces and extending into engagement with the other of said frame pieces. 70

23. In a loose leaf binder adapted to contain record leaves, two series of impaling prongs, means for mounting and guiding the series of impaling prongs for movement away from each other to permit removal or addition of record leaves, means mounting the impaling prongs of one series for angular movement to stagger their ends with respect to the impaling prongs of the other series to effect longitudinal shifting of said leaves with respect to each other, and means actuated by the movement of the series of impaling prongs towards each other for moving the movable prongs to the normal angular position. 80

In witness whereof I have hereunto set my hand this 5th day of October 1928.

JOHN L. McMILLAN.
